UNITED STATES PATENT OFFICE.

ALFRED KURT FUNGER, OF DRESDEN, GERMANY, ASSIGNOR TO THE FIRM EDMUND KLETZSCH, OF COSWIG, SAXONY, GERMANY.

SCREW PROPELLER.

Application filed November 25, 1924, Serial No. 752,145, and in Germany January 8, 1924.

All heretofore known screw propellers for wind turbines or the like consist of a continuous screw surface whose pitch is at first steep and then diminishing towards the outer end of the propeller wing. It has been found to be impossible to so shape said propeller wing, as to afford the highest degree of efficiency first in respect to the driving power and secondly in respect to the mechanical effect. Apart from this, in almost all cases, there remains a zone on the propeller wing in which the wind power is not fully effective. It is well known that to produce a powerful drive, it is necessary that at the inner part of the propeller wing, i. e., the one directed towards the center, the pitch be high (starting say with 45°), while the outer part on which the wind power acts must have a proportionately much smaller pitch. These two conditions cannot be attained in a continuous propeller surface. In practice always one condition will have to be subordinated to the other condition.

The invention has for its object to solve this problem by dividing the propeller wing longitudinally preferably into two sections. The inner section, i. e., the section directed towards the center of the turbine wheel can then, irrespective of the requirements as to the outwardly directed section, be given a high pitch and the outer section serving for the power transmission may be given the desired lower pitch. When the two sections can be separately fixed on the known ring supports of the turbine wheel, it is advantageous to join them at their junction by an angle piece shaped so that the two sections of the propeller, when fixed to the angle piece are properly positioned. To this end, the angle piece is formed with flanges, which are curved not only to conform with the pitch of the adjoining sections, but are also so displaced relative to one another that the two sections of the propeller intersect one another.

The angle piece may also be provided with a guide for the ring body joining the individual propeller wings, in order that when assembled the latter becomes properly positioned.

It is further advantageous that the edge of the propeller wing, which relative to the direction of rotation is directed rearwardly, be bent upwardly in the outward direction, i. e., rearwardly relative to the direction of

the wind. This affords space for the rings joining the propeller wings and at the same time favorable current conditions, since an under pressure is produced in the vicinity of this edge on the side of the propeller wing directed opposite the wind, that enables this edge to pass without any resistance through the air current.

One embodiment of this invention is illustrated in the accompanying drawing in which similar reference characters denote corresponding parts and in which Fig. 1 is a perspective view of the air turbine wheel; Fig. 2 a front elevation of my new propeller wing according to its geometrical shape; Fig. 3 a front elevation of the spirally shaped propeller wing; Fig. 4 a view of the outer end of the propeller wing; Fig. 5 a cross section at the junction of the wing sections; Fig. 6 an elevation of an angle piece serving as a joint for the two wing sections; Fig. 6^a a plan view thereof; Fig. 6^b a vertical cross section on line 6^b—6^b of Fig. 6; Fig. 6^c a similar cross section on line 6^c—6^c of Fig. 6^a; Fig. 7 shows diagrammatically the arrangement of the two wing sections displaced relative to or separated from one another.

In the example shown, the propeller wing is composed of two sections *a* and *b*.

The section *b*, which relative to the center of the wheel constitutes the inner section, is curved in form of a screw with a high pitch, which, for example, at δ may be 45° and at γ may be 30°. The second section *a*, which relative to the center of the wheel is directed outwardly, begins with a smaller pitch, say 22°, at β , and ends with an angle of 10° at α . In this manner, the highly curved inner section *b* is particularly adapted to produce a powerful drive, while the section *a* acts as an excellent means for transmitting the power. The transmission zone being eliminated, there is nowhere on the wing surfaces a part of inferior efficiency.

For joining the two wing sections, whose relative positions are seen in Fig. 5, I employ an angle piece shown in Figs. 6, 6^a, 6^b and 6^c. This angle piece consists of a body portion *c* formed with flanges *d*, *e*. Section *a* of the wing is riveted or otherwise fixed to the flange *d* and the section *b* to flange *e*, as indicated by dotted lines in Fig. 6. The flanges *d* and *e* are curved at their junction in conformity with the curvature of the cor-

responding wing sections, so that the wing sections bear evenly thereon. The flanges are also displaced or arranged to intersect one another, as a result of which the adjoining ends of the wing sections are located on different levels, the same intersecting one another only in the longitudinal central line, as seen from Figs. 3 and 5. This angular member insures proper positioning of the 10 two wing sections, when assembling the same.

In order that the propeller wing be properly positioned in the wheel, the body portion *c* is provided with a U-shaped extension.

f. The latter is formed with two longitudinal end flanges *g*, which form between themselves a groove. In this groove constituting a socket is adapted to fit the well-known ring member, that serves to join all propeller wings to the turbine wheel, and which is adapted to pass through a slit *h* of the angle piece.

As seen from Fig. 4, the wing section *a* in the vicinity of the edge *i*, which, relative to the direction of rotation, is directed rearwardly, is bent outwardly relative to the direction of the air current indicated by the arrows *x* in Fig. 4. By this bend, not only is space provided for the accommodation of the usual fastening ring, which is arranged in well-known manner near the outer end of the wing section *a*, but additionally an under pressure or even suction is produced behind said edge *i*, so that the bent edge, during the rotation of the wheel, always passes through 35 an almost completely evacuated space and thus does not meet with any appreciable resistance.

What I claim is:—

1. In a wind turbine, a screw propeller wing composed longitudinally of a plurality of separate screw curved sections having different outwardly diminishing pitch.

2. In a wind turbine, a screw propeller wing composed longitudinally of a plurality of separate screw curved sections of different pitch and means for joining said sections together curved in conformity with the pitch of said sections. 45

3. In a wind turbine, a screw propeller wing composed longitudinally of a plurality of sections of different pitch and an angle piece for joining said sections together, said piece having flanges curved in conformity with the pitch of said sections and intersecting one another. 50

4. In a wind turbine, a screw propeller wing composed longitudinally of a plurality of screw curved sections of different outwardly diminishing pitch, the outwardly directed section having its edge, which relative to the direction of rotation is located at the rear of the propeller wing, bent outwardly or rearwardly relative to the air current. 55

5. In a wind turbine, propeller wings, each composed longitudinally of a plurality of sections, an angle piece for joining the sections of each propeller wing together, each angle piece being formed with a socket and an annular member passing through said sockets for holding said propeller wings together in proper position on the turbine wheel. 60

6. In a wind turbine, a propeller wing divided longitudinally into a plurality of sections, each of which is twisted into the shape of a screw of different pitch, so as to form an interrupted screw line, the end of each wing section directed toward the center being at a higher pitch relative to the direction of motion than that of the end directed toward the periphery. 75

In testimony whereof I affix my signature.

ALFRED KURT FUNGER.
